ALBERT ILLIAS, OF NEWARK, NEW JERSEY.

ATTACHMENT FOR INTERNAL-COMBUSTION ENGINES.

1,341,172.

Specification of Letters Patent.

Patented May 25, 1920.

Application filed November 29, 1918. Serial No. 264,581.

To all whom it may concern:

Be it known that I, ALBERT ILLIAS, a resident of the city of Newark, in the county of Essex and State of New Jersey, have invented certain new and useful Improvements in Attachments for Internal-Combustion Engines, of which the following is a specification.

The present invention relates to an attachment for internal combustion engines, which is to be inserted into that pipe of the engine that conveys the combustible mixture to the engine.

The main object of the invention is to provide a simple, compact and inexpensive contrivance for enabling an intimate and correctly proportioned and regulated mixture of hydrocarbon and air to be supplied to the cylinders of the engine or other points of consumption.

Another object of the invention is to devise the attachment, that it serves also as a means for indicating the proper operation of the valves of the engine.

With these and other objects in view which will more fully appear as the nature of the invention is better understood, the same consists in the combination, arrangement and construction of parts hereinafter described, pointed out in the appended claim and illustrated in the accompanying drawings, it being understood that many changes may be made in the size and proportion of the several parts and details of construction within the scope of the appended claim without departing from the spirit or sacrificing any of the advantages of the invention.

One of the many possible embodiments of the invention is illustrated in the accompanying drawings, in which:

The figure is a central vertical section taken through a device constructed in accordance with the present invention.

In the drawings, the numeral 1 indicates the inlet pipe or intake-manifold of an internal combustion engine. This manifold communicates with a carbureter 2 of any suitable construction, the one herein shown being disclosed for purposes of illustration only.

The attachment is denoted by the numeral 3, and comprises a horizontally disposed cylindrical casing 4, closed at both of its ends by heads 5, and provided with a central vertical partition 6, which divides the said

casing into two non-communicating compartments. In each of these compartments is reciprocably disposed a piston 7, to each piston being attached a rod 8, which extends through the respective head 5. The outer, free end of each rod 8 is screw threaded, as shown at 9, the said threads being in mesh with a nut 10, serving as an abutment for a spring 11, the other end of which bears against the respective head 5 of the cylindrical casing. On either side of the partition 6 is formed a plurality of apertures 12, which lead from the respective casing compartment to a chamber 13, that communicates through a pipe 14 with the intake-manifold 1. The pipe 14 is tapped into the intake-manifold, preferably, opposite to the discharge opening of the carbureter, as clearly appears from the drawing. In the pipe 14 is provided a throttle valve 15, for a purpose hereinafter to be described.

The tension of the springs 11 may be varied, according to the requirements, by changing the positions of the nuts 10 on the rods 8. Around each piston rod is coiled, within the casing 4, a spring 16, adapted to bear against the inner face of the respective head 5 and against the respective piston 7. The purpose of these springs is to prevent the pistons from being forcibly thrown by the springs 11 or by a back-fire against the casing heads. A resilient block 17 on the partition 6 serves to prevent the pistons from being drawn against the said partition, as will hereinafter appear.

In each piston is provided a plurality of openings 18, which are controlled by inwardly opening check valves 19. The stems 95 of these valves project beyond the pistons toward the respective heads 5, thereby unseating the valves when the pistons are, for instance, in case of back-fire in a cylinder of the engine forcibly thrown against the heads 5. When the valves are unseated, the pressure in the casing compartments is released, the gas flowing in rear of the pistons and thence through openings 20 in the casing heads 5 to the atmosphere. Springs 21 on the stems of the valves 19 seat the said valves, as soon as the pistons move in the opposite direction.

The operation of the device is as follows:—When suction occurs in the intake-manifold of the engine, air is drawn through the carbureter, the said air rushing up past

the nozzle thereot and drawing out a certain amount of fuel, depending upon the volume of air passing said nozzle. At the same time the pistons 7 in the casing 4 are drawn, against the action of the springs 11, toward the partition of the said casing. As soon as the suction ceases, the springs 11 cause the pistons to move toward the heads 5 which movement induces a flow of air through the carbureter past the nozzle thereof, carrying along with it a certain amount of fuel into the chamber 13, and through the apertures 12 into the compartments of the casing 4. On the next suction stroke, the mixtures in the two compartments of the casing 4 are drawn into the engine cylinders, in addition to the hydrocarbon and air from the carbureter. The play now described is repeated during each cycle of operation within the cylinders of the engine. It will be observed that the attachment is, in fact, a pump for producing, in coöperation with the carbureter, a suitable mixture of liquid hydrocarbon and air, which pump is actuated by the suction produced by the working pistons of the engine. It produces, however, a mixture at times when and as long as the suction in the intake-manifold ceases, or in other words at times when there is no production of mixture in the carbureter of the engine.

The attachment serves also as a storage vessel, as it were, for a mixture of air and hydrocarbon, and this mixture is transferred to the cylinders of the engine, when a combustible mixture flows from the carbureter through the intake-manifold. Since, however, the mixtures from the casing 4 and the carbureter flow toward each other, they are effectively mixed before passing to the engine.

The uniformity of the mixture is influenced by this attachment for the reason that a too lean mixture passing from the carbureter at the beginning of the suction stroke of a working piston is supplemented by the mixture stored in the casing 4, and a too rich mixture passing from the carbureter at the time of the most effective vacuum in an engine cylinder is made more proportionate when commingled with the mixture in said attachment.

It is obvious that, since the quality and quantity of the combustible mixture is thus regulated and a complete combustion takes place in the cylinders of the engine, a quiet running of the engine will be the result, and that the walls of the cylinders of the engine will be kept clear as there are no loose carbon particles flowing in the products of combustion.

The opening in the carbureter nozzle can

be obviously made smaller than in carbureters heretofore in use, for the reason that the time during which air rushes past the said nozzle is doubled by the attachment, consequently a fine spray of liquid hydrocarbon will issue from said nozzle, which can be in a more effective way carbureted. This, of course, results in a saving of fuel. 70

When a rich mixture is required, as in case of starting, the valve 15 is set to its closing position, thereby eliminating the attachment.

If during the operation of the engine some 75 of its exhaust valves do not close properly, for instance if a valve or its seat is worn, the springs 11 on the piston rods 8 work irregular, thereby clearly indicating the fact that the engine valves do not close properly. 80

When the engine is running idle, the carbureter throttle is obviously set to its almost closing position. In such case, a high vacuum is produced within the intake-manifold, which causes the pistons 7 in the casing 4 of the attachment to come to their innermost positions, in which they close the apertures 12 in said casing. Due to the high vacuum and also to the fact that the suction strokes follow each other almost without interruption, the pistons will be held in these innermost positions, so that the attachment is eliminated. This is desirable, as for idling very little fuel is needed.

What I claim is:—

The combination with the intake-manifold of an internal combustion engine, of a carbureter communicating therewith, a cylindrical casing having a central partition and being provided with apertures on either side of 100 said partition through which said casing communicates with a chamber, said chamber also communicating with said intake-manifold, a piston in each compartment of said casing adapted to reduce the space in the 105 respective compartment to a minimum by the suction produced in said intake-manifold by the working of a piston of the engine, means disposed outside of said casing for returning said pistons to their normal positions when the suction in said intake-manifold ceases, and means for closing the communication between said chamber and said intake-manifold, the heads of said casing being provided with openings and each of 110 said pistons having openings controlled by inwardly opening check valves adapted to be unseated when said pistons are forced against said heads.

Signed at New York, in the county of New 120 York, and State of New York, this 1st day of August, A. D. 1918.

ALBERT ILLIAS.
